COMBINED TRAY AND HOLDER FOR ARTIST'S SUPPLIES

Glenn C. Hammond, Akron, Ohio

Application January 3, 1956, Serial No. 39,576

Term of patent 14 years

(Cl. D33—3)

FIG. 1

FIG. 3

Fig. 1 is a perspective view of a combined tray and holder for artist's supplies showing my new design.

Fig. 2 is an elevational view thereof with portions thereof broken away; and

Fig. 3 is a top plan view of the tray element of the combination.

I claim:

An ornamental design for a combined tray and holder for artist's supplies, substantially as shown.
